UNITED STATES PATENT OFFICE.

BERNHARD DREYFUS, OF NEW YORK, N. Y.

DESIGN FOR A PENDANT.

SPECIFICATION forming part of Design No. 16,070, dated May 5, 1885.

Application filed March 11, 1885. Term of patent 7 years.

To all whom it may concern:

Be it known that I, BERNHARD DREYFUS, of the city, county, and State of New York, have invented a new and original Design for 5 Pendants, of which the following is a full, clear, and exact description.

Reference is to be had to the accompanying drawing, in which a side view of my new design for pendants is shown.

10 A is a cylindrical drop having a fuzzy outer surface.

B is a cylindrical part consisting of a series of radially-projecting loops around a central core, which part B has a smaller diameter than 15 the cylindrical drop A, and extends downward from the bottom of the same.

C is a bead or ball at the lower end of the part B.

D is a slung ruff at the top of the cylindri- 20 cal part A.

E is a bead or ball above the slung ruff D, and F is a loop.

Having thus described my invention, I claim as new and desire to secure by Letters Patent—

1. The design herein shown and described 25 for pendants, consisting of the parts A and B, having different diameters, and a shoulder or offset where the parts of different diameters meet, and the bead or ball C on the lower part of the part B, substantially as set forth. 30

2. The herein shown and described design for pendants, consisting of the parts A B, the slung ruff D, and the bead E at the top of the part A, substantially as set forth.

3. The herein shown and described design 35 for pendants, consisting of the parts A and B, the bead C on the lower end of the part B, the slung ruff D, the bead E, and the loop F at the top of part A, substantially as set forth.

BERNHARD DREYFUS.
